CLAIM

The ornamental design for a universal ground bow stand, as shown and described.

DESCRIPTION

FIG. 1 is a perspective view of a universal ground bow stand embodying my new design;

FIG. 2 is an enlarged perspective view thereof;

FIG. 3 is a front view thereof;

FIG. 4 is a back view thereof;

FIG. 5 is a top view thereof;

FIG. 6 is a bottom view thereof; and,

FIG. 7 is a side view thereof, the opposite side being a mirror image thereof.

The broken lines shown in FIG. 1 represent portions of the universal ground bow stand that form no part of the claimed design.
